(Cl. D34—13)

To all whom it may concern:

Be it known that I, Dorothy E. Whiting, a citizen of the United States, residing at Fairfield, in the county of Fairfield, and State of Connecticut, have invented a new, original, and ornamental Design for a Holder for a Hand of Playing Cards, of which the following is a specification, reference being had to the accompanying drawing, forming part thereof.

In the drawings:

Fig. 1 is a perspective view from the front, of a holder for a hand of playing cards showing my new design.

Fig. 2 is a front elevation.

Fig. 3 is a side view.

Fig. 4 is a top plan view.

I claim:

The ornamental design for a holder for a hand of playing cards, substantially as shown.

DOROTHY E. WHITING.
